DEVICE FOR THE WET TREATMENT, REMOVAL OF MOISTURE FROM, AND DRYING OF BALLS OF THREAD OR THE LIKE

Fritz Gottfried Schumacher, Basel, Switzerland

Application December 6, 1933, Serial No. 701,243
In Germany December 23, 1932

1 Claim. (Cl. 8—19)

Devices are already known for the wet treatment, removal of moisture from and drying of balls of thread or the like to which the several agents used for treatment are forced through 5 the material successively by centrifugal action. In the known devices there are several containers arranged one above the other for receiving the treating agents, the topmost of these containers being used as a common feed chamber 10 for all the agents with which the yarn is treated. The defect of this arrangement is that transmission to the balls of thread was only effected by the suction of the worm arranged in the interior of the spindles. The quantity of agent 15 which is driven through the material is controlled mainly by the difference in pressure between the interiors of the spindles and the outside of the balls.

It has also been proposed to rotate balls of 20 thread in a closed container filled with liquor and to effect a rotating movement of the liquor in the container by a centrifugal wheel arranged in the bottom. The effect of a revolving device of this kind is very slight because the action of 25 the centrifugal force can only be developed to a very slight extent in the ball of thread.

These deficiencies are according to the invention obviated inasmuch as the several containers for receiving the balls, which containers are shut 30 off from the outside air, are connected up in such a way to the corresponding liquor delivering agencies, in particular blade wheels or the like, that any collection of liquor outside the material cannot occur.

35 In order at the same time to provide for continuity of operation a distributing means is provided between the containers and the centrifugal device, which means at the same time regulates or controls the admission and discharge.

40 On the drawings a constructional form of the invention is illustrated, in which Figure 1 is a diagram of the arrangement of a centrifugal dyeing device on a container consisting of three chambers. Fig. 2 is a plan of the dyeing machine for twelve centrifugal dyeing devices. Fig. 3 is a longitudinal section through a centrifugal dyeing device. Fig. 4 is a longitudinal section through a distributing agency. Fig. 5 is a section through the line 5—5 of Fig. 4 and Fig. 6 45 is a section through the line 6—6 of Fig. 4. Fig. 7 is a section of a modified form of the centrifugal dyeing device. Fig. 8 is a section through the line 8—8 of Fig. 7.

50 The machine consists of the container 10, which contains three chambers, 11, 12 and 13,

which can in any desired way, preferably by jacket heating, by electricity or steam, be raised to the desired temperature. In the bottom chamber 11 there is the dyeing liquor, in the chamber 12 the washing liquid, and the top chamber 13 contains an air heater of any desired kind.

5 On the outside wall of the container 12 there are arranged for example 12 centrifugal dyeing devices each of which is fixed by means of a base 14 to the container 10. The base 14 has double ball-bearings 15 which serves as the mounting for a hollow-shaft 16. At the top end of the bottom shaft there is a screw pin 17 on which a bobbin spindle 18 can be screwed. This bobbin 15 spindle 18 is hollow and has on the outside longitudinal grooves 19 which communicate with the bore by apertures 20 of any form. Over this spindle 18 the bobbin 21 is skewered, being shaped or formed on a sleeve 22 provided with 20 perforations.

The hollow shaft 16 also has at its upper end a blade wheel 23, the blades of which open into a spiral housing 24, which is mounted on the base 14. A perforated casing 25 is fixed by the 25 flange 26 to the blade wheel 23. In the casing 25 a glass jacket is fixed by a screw ring 28, which is securely held in its position with the aid of the packings 29. The casing 25 participates in the rotation of the blade wheel 23 and consequently in the rotation of the hollow shaft 16. 30 At the upper end the casing 25 is shut off by a cover 30, which can be fixed to the casing 25 by a bayonet joint 31. The packing between the casing 25 and the cover 30 is a rubber ring 32. 35

On the cover 30 a pin 33 is fixed to the middle, on which a conical head 34 can slide. This head 34 is under the action of the spring 35, and in its hollow it has a packing 36 by which it can press down on the bobbin 21. This head 40 not only comes to lie close against the bobbin 21 but also presses them firmly on the spindle 18.

At the bottom end of the hollow shaft 16 a ring 37 is screwed which serves to secure the ball bearing 15, and has clutches 38 on its under face. 45 With the clutches 38 there engage the clutches 39 of a hollow shaft 40 of the motor 41, which is fixed to the container by means of the base 41a. The electric motor 41 effects the rotation of the hollow shaft 16, and thereby of the blade 50 wheel 23 the casing 25, and the bobbin 21.

Through the hollow shaft 40 of the motor and the hollow shaft 16 a stationary pipe 42 passes, which serves to feed in the media from the container 10. In the screw neck 17 a screw spin- 55

idle 43 is fixed which conveys the media in the tube 42 upwards to the hollow bobbin spindle 18.

The bottom end of the pipe 42 is fixed to a short pipe 44 of a distributing agency (Fig 4-6). This distributing agency is fixed in any desired way to the container 10.

The distributing agency consists of the casing 45 in which a cone 46 is turnable, which, by means of a centre partition 47 forms two chambers 48 and 49 in the distributing agency. The cone 46 has a shaft 50, which is closely guided in the casing cover 51 and carries on the outer end an indicator disc 52, with handle 53. A spring 54 tends to press the cone 46 on its seat. The casing 45 has three short pipes 55, 56, 57, staggered at an angle of 120°, through which the corresponding media can pass from their containers 11, 12 and 13 into the chamber 48. To the chamber 49 there are also connected up three short pipes 58, 59, 60, the first two of which also lead to the containers 11, 12, while 60 only carries a pipe leading into the open air. In the chamber 49 there likewise ends a short pipe 61 which is in communication with the outlet of the spiral casing 24. The cone 46 has two passage openings 62 and 63, the former of which leads into the chamber 48 and is of just the right size in order successively to expose the bore of the pipes 55-57. The opening 63 lies on the same line of the jacket as the opening 62, but is elongated so that it still keeps the bores of the pipes 58-60 open, when the bores of the pipes 55-57 are closed. The object of this arrangement is to permit of the outflow of the excess of media still present in the centrifugal dyeing device, even when the inflow is already shut off.

The way in which the device, according to Figs. 1-6 operates, is as follows: After starting the centrifugal dyeing device the distributing agency is put into the position Figs. 4-6. The screw spindle 43 then exerts suction on the liquid in the chamber 11, the latter being drawn through the chamber 48. The liquid rises up in the pipes 42, and reaches the hollow bobbin spindle. From here the liquid is forced through the bobbin body 21 by the feed pressure and the centrifugal action. As at the same time a vacuum is created in the casing 25 by the blade wheel 23, the liquid will be able to pass through more easily. The liquid which gets into the casing runs into the blade wheel, and is conveyed by the latter to the pipe 61 of the distributing agency from where again through the pipe 58 it reaches the container 11. When the bobbin 21 has been sufficiently treated the cone 46 is turned to such an extent that the pipe 55 is shut off. The inflow is thus stopped. The liquid present in the centrifugal dyeing device is, however, then still able to flow out through the opening 63 which is still open and the pipe 58 until it is quite emptied out.

Thereupon the cone 46 is turned till the openings 62 and 63 lie over the pipes 56 and 59. The container 12 is now connected up to the distributing agency so that now the same operations as described above are repeated with the liquid present in the container 12.

On the termination of this process the tap is again turned and the openings 62 and 63 brought over the pipes 57 and 60. The centrifugal dyeing device is now connected up to the air heater 13, so that the bobbin 21 is now dried by the hot air passing through. In order, after the completion of all the processes, to conduct all liquids back

into the containers, which should stand up to the volume distributing agency there is provided a small orifice 64, for admission of air, which allows air to enter into the distributing agency through opening 63.

In the device illustrated in Figs. 1 to 6 the feeding and production of pressure inside the spindle takes place by means of the worm 43 arranged in the spindle. In many cases, however, the pressure produced by a worm is not sufficient to drive the media through the material. Furthermore, it is not always desirable to bore through the shaft of the driving motor. In addition, it is necessary to empty completely all parts of the medium conveying device, in order to prevent the media getting mixed up in the device on changing over from one medium to the other. This is particularly necessary when changing over from the moistening liquid to the dye.

These defects are avoided in the fullest measure in the arrangement according to Figs. 7 and 8. The spindle 18 with the bobbin 21 has the same form as in the arrangement according to Fig. 1. Rotation of the spindle 18 is effected by a shaft 66, which runs in two ball bearings 67 and 68 of a housing 69 which can be fixed to the container 10 by the base 70 in the same as according to Figs. 1-3. The drive of the shaft 66 is by a normal vertical motor 71 through the medium of a coupling 72. Above the bearing housing 69 a centrifugal pump housing 73 in which the rotor impeller wheel 74 which is fixed on the shaft 66 by groove and tongue, works. The casing 75 is closed above by a channelled cover 73a, in which a channel conveys the medium transmitted by the rotor to the shaft 66. Above the top of the channelled cover the shaft is provided with a screw thread 75, of several turns, on which a second rotor 76 is fixed, for example by shrinking on. From the channelled cover 73a a passage 77 leads to the screw thread 75. Inside the wheel 76 a passage channel 78 abuts on the screw thread 75, and leads to the interior of the spindle 18. The rotor impeller wheel 76 runs similarly as in Fig. 3 in a casing 79 which can be connected with the casing 73 and the channelled cover 73a by screws or the like. The casing 79 has a perforated bearer 81, the walls of which are formed by a glass jacket 82. This bearer 81 and the glass jacket 82 however, remain stationary. The bearing 81 is shut off above by a cover 83 which can be secured to the bearer 81 by a bayonet joint or by other suitable method of fastening.

As in the present case, the cover 83 does not share in the rotation of the bobbin, the head 34 with its elastic springing, is turnable in the cover 83 on a ball bearing 84. In order to be able to connect up the bottom centrifugal pump to the containers 11, 12 and 13, the suction chamber 85 has three connecting pipes 86. The top casing 79 also has three connecting pipes 87. The pipes 86 and 87 are arranged vertically above one another so that two of them at a time can always be connected up to pipes 88 and 89 of a cock body 90. In the cock body 90, a cone 91, is fitted turnable by a hand wheel 92, which cone by a wall 93 divides off two chambers 94 and 95 in the body 90. The bottom chamber 94 communicates with a pipe 96 to which a pipe 97 can be connected up. This pipe 97 leads each time to the several containers 11, 12 and 13 respectively. This pipe 97 forms the suction pipe of the centrifugal pump, and leads to the containers containing the liquid 75.

media are connected up to the latter near the bottom. In each case, however, the connecting pipe 96 must lie higher than the highest level of liquid in one of the containers 11, 12 or 13. On the 5 other hand, the tube 97 of the cock which leads to the air heater, is connected up to the upper end of the air heater, and it is immaterial whether the air heater is high or low. The top chamber 95 of each cock has an outlet aperture 98 which communicates with a short pipe not shown, which in its turn is connected by a pipe with the same container 10, 11 or 12, as the pipes 97. The pipes coming from the outlet opening 98, however, and above the liquid in the corresponding 15 containers. In the case of the cock which only contains hot air, a connection for conveying away is not necessary, but a pipe leading into the open air may preferably be provided, as shown in Fig. 1, pipe line 60.

20 The openings 99 and 100, which act on the pipes 96, and 97, and also the opening 101, which acts on the outlet opening 98, are so designed that the outlet 98 is still almost fully open when the opening 99 is already nearly closed. Shortly 25 before the complete closing of the opening 99, a channel 102 in the cock plug 94 comes in front of an opening 103 in the housing 90, so that now

the rotor impeller 74 draws air but no liquid. The liquid in circulation from time to time in the centrifugal dyeing device no longer gains admission and is gradually expelled. Only now is the cock in question completely closed, and following thereon the next cock is opened. In what way the media pass through the centrifugal dyeing device is shown by the arrows.

5

I claim:—

An apparatus for the treatment of yarn in 10 balls or cops comprising a container divided into three superposed compartments, a plurality of dyeing, washing and drying members surrounding said container, means for fixing said members to the side of the container, said members radiating 15 from said container, hollow shafts carried by said members, blade wheels carried by the upper ends of said hollow shafts, spiral casings enclosing said blade wheels, bobbin spindles fixed to the upper ends of said hollow shafts, separate 20 motors mounted for rotating the hollow shafts and bobbin spindle, pipes connecting the compartments with the dyeing, washing and drying members for the conveyance of treatment media and a multiway valve connected with said pipes 25 controlling the treatment media.

FRITZ GOTTFRIED SCHUMACHER.
